(57) **CLAIM**

The ornamental design for a nasal epilation wax heater as shown and described.

DESCRIPTION

FIG. 1 is a top, front and right side perspective view of a nasal epilation wax heater showing my new design; FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top, front and right side perspective view showing the nasal epilation wax heater in a state of use; and,

FIG. 10 is a top, front and right side perspective view showing the nasal epilation wax heater in another state of use.

In the drawings, the equal-length broken lines depict portions of the nasal epilation wax heater that form no part of the claimed design.

1 Claim, 10 Drawing Sheets
